UNITED STATES PATENT OFFICE

ERNST KELSEN, OF VIENNA, AUSTRIA

APPARATUS FOR ELECTROLYTICALLY PRODUCING METAL ALLOYS

Application filed August 22, 1928, Serial No. 301,339, and in Austria August 24, 1927.

The invention relates to an apparatus for carrying out the known process of electrolytically producing metal alloys, in which by the alternate formation of superposed layers of the single metals, of which the alloy is to be composed, the alloy is obtained in a purely electrolytic way. For this purpose for instance soluble anodes of the respective metals, each of which anodes is connected to a source of electric current, are brought to coact with a common rotary cathode. In a known apparatus for carrying out this method, a cathode having the form of a solid traced out in revolution (for instance that of a cylinder) is moved along baths containing the different electrolytes, closing of the circuit being brought about thereby; in this apparatus the deposited metal mass is on the way between the several electrolytic baths pressed and smoothed by means of polishing tools, particularly suitable smoothing stones (agates), this method being known as Elmore process. In order to be able of doing so only small sections of the mantle surface of the rotary cathode were successively brought into contact with the electrolytic baths, and in the interstitial spaces between the baths polishing stones and appliances for rinsing or washing the deposits were arranged.

According to the present invention in an apparatus of the aforementioned type between the mantle surface of the rotating, for instance cylindrical cathode and the adjacent surfaces of the walls of the tanks or vats containing the electrolytes a clearance is provided in order to prevent the deposit formed on the mantle where passing through the bath from being scoured off as the cathode continuously rotates, and underneath each electrolytic tank a receptacle is placed, which takes up the portions of electrolyte leaking out through the clearances. In connection with each of these collecting receptacles a pipe duct with a pump is provided, which drives the liquid back into the respective electrolytic tank. By this way the possibility is given of increasing the speed of rotation of the cathode to such degree, that extremely thin layers of deposit are formed, which

without any further treatment are for themselves of sufficient density, so that the operations of pressing, smoothing and washing the deposited metal layers between the several baths can be dispensed with. Moreover the further possibility is given thereby of arranging the different baths around nearly the entire mantle surface of the rotary body constituting the cathode.

According to a special and particularly advantageous feature of the invention means for purifying the liquid may be combined with the device for leading back the electrolyte into the electrolytic tanks. For this purpose the receptacles placed below the electrolytic vats may constitute filters themselves or else they may be combined with separate filtering appliances.

In the drawing an embodiment of the invention is shown by way of example, Fig. 1 being a sectional elevation and Fig. 2 a plan view.

1 and 2 are the vats or tanks containing the different electrolytes for forming the different metallic deposits and 3 is a cylindrical cathode electrically connected to the circuit by means of brushes and wires 7. This cylinder protrudes by its mantle through a suitably shaped opening in a side wall of each electrolytic tank thus constituting part of the respective wall and is rotated by any suitable means. 8 and 9 are soluble metal anodes with terminals and electric line wires 10 and 11. Below the tanks the collecting receptacles 4 and 5 are placed, which take up the portions of electrolyte escaping through the clearances between the cylinder and the edges of the walls of the tanks 1 and 2. By pumps 6 the electrolytes are sucked up through the pipes 12 and driven back into the respective electrolytic tanks through the pipes 13.

What I claim is:

1. An apparatus for electrolytically producing metal alloys, which apparatus comprises a rotary cathode, a plurality of tanks containing different electrolytic baths, which tanks are arranged around the cathode in such manner, that the cathode will be successively put into contact with each of the said different baths and that between the rotary cathode

and the edges of the tank walls formed by said arrangement there remain clearances, receptacles placed underneath the tanks for collecting the electrolytes escaping by leakage through said clearances and means for leading back the collected electrolytes into the respective electrolytic tanks.

2. An apparatus for electrolytically producing metal alloys, which apparatus comprises a rotary cathode a plurality of tanks containing different electrolytic baths, which tanks are arranged around the cathode in such manner, that the cathode will be successively put into contact with each of the said different baths and that between the rotary cathode and the edges of the tank walls formed by said arrangement there remain clearances, receptacles placed underneath the tanks for collecting the electrolytes escaping by leakage through said clearances, means for leading back the collected electrolytes into the respective electrolytic tanks and a filtering device combined with the means for leading back the electrolytes.

25 3. An apparatus for electrolytically producing metal alloys, which apparatus comprises a rotary cathode a plurality of tanks containing different electrolytic baths, which tanks are arranged around the cathode nearly to the entire extent of its mantle surface in such manner, that the cathode will be successively put into contact with each of the said different baths and that between the rotary cathode and the edges of the tank walls formed by said arrangement there remain clearances, receptacles placed underneath the tanks for collecting the electrolytes escaping by leakage through said clearances and means for leading back the collected electrolytes

40 into the respective electrolytic tanks.

4. An apparatus for electrolytically producing metal alloys, which apparatus comprises a rotary cathode, a plurality of tanks containing different electrolytic baths, which tanks are arranged around the cathode nearly to the entire extent of its mantle surface in such manner, that the cathode will be successively put into contact with each of the said different baths and that between the rotary cathode and the edges of the tank walls formed by said arrangement there remain clearances, receptacles placed underneath the tanks for collecting the electrolytes escaping by leakage through said clearances, means for leading back the collected electrolytes into the respective electrolytic tanks, and a filtering device combined with the means for leading back the electrolytes from the said receptacles into the respective tanks.

60 In testimony whereof I have affixed my signature.

ERNST KELSEN.
